[57] CLAIM

The ornamental design for a computer keyboard, as shown and described.

DESCRIPTION

FIG. 1 is a front elevational view of a computer keyboard showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an enlarged cross-sectional view thereof taken along the line VII—VII in FIG. 1, with most of the internal structure omitted;

FIG. 8 is a top, front, right side perspective view thereof, the keyboard being engaged with the base;

FIG. 9 is an exploded perspective view thereof, the keyboard being disengaged from the base;

FIG. 10 is a top, front, left side perspective view thereof, the fitting used to connect the keyboard to a personal computer in the extended position.
